Primary Examiner — Catherine S Posthauer*Assistant Examiner* — Joan E. Diehl(74) Attorney, Agent, or Firm — Morgan, Lewis & Bockius LLP(57) CLAIM

The ornamental design for a bottle, as shown and described.

DESCRIPTION

FIG. 1 is a front perspective view of a bottle showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines illustrate portions of the article that form no part of the claimed design. The dash-dot-dash lines represent boundaries of the claim and form no part thereof. The sunburst shape forming part of the claimed design is a registered trademark of Sombra Holdings LLC.

1 Claim, 7 Drawing Sheets(56)
